UNITED STATES PATENT OFFICE.

STEPHEN M. SOULE, OF PALMYRA, NEW YORK.

STOVEPIPE-HOLDER.

1,159,117.

Specification of Letters Patent.

Patented Nov. 2, 1915.

Application filed June 18, 1914. Serial No. 845,887.

To all whom it may concern:

Be it known that I, STEPHEN M. SOULE, a citizen of the United States, residing at Palmyra, in the county of Wayne, State of New York, have invented certain new and useful Improvements in Stovepipe-Holders; and I do hereby declare the following to be a full, clear, and exact description of the invention, such as will enable others skilled 10 in the art to which it appertains to make and use the same.

This invention relates to improvements in stove pipe holders, and particularly to devices for holding stove pipes within flue 15 openings.

The principal object of the invention is to provide a simple and adjustable device by means of which the stove pipe can be detachably and securely held within a flue 20 opening.

Another object is to provide a simple and cheap device of this character which is capable of use in any flue opening or in connection with any stove pipe.

Other objects and advantages will be apparent from the following description, when taken in connection with the accompanying drawings.

In the drawings: Figure 1 is a top plan view of the device, a portion of the stove pipe being shown connected therewith and a portion of a flue being shown in section. Fig. 2 is a vertical longitudinal sectional view on the line 2—2 of Fig. 1. Fig. 3 is a 35 perspective view of the device removed from the flue and pipe.

Referring particularly to the accompanying drawings, 10 represents a portion of a stove pipe thimble in which the stove pipe 11 is to be secured.

The invention comprises a lower plate 13, an upper plate 14, and an intermediate plate 15. The plate 13 has a ring 16 formed at the rear end and adjacent the opposite end is formed with a vertical opening 17. The intermediate plate 15 is formed with an opening 18 in the end corresponding to the apertured end of the plate 13 which receives the bolt 19. The plate 14 is formed with an elongated slot 21 through which the bolt 19 is disposed and against which is screwed a

nut 22 carried by the bolt. The forward end of the plate 14 is turned downwardly as indicated at 23 and is arranged to engage with the inner face of the flue at the lower side 55 of the opening, while the ring 16 engages the wall below the flue opening within the room. The rear end of the intermediate plate 15 has an upwardly curved portion 24 and between this plate 15 and the plate 13 is inserted the lower portion of the stove pipe 11, the pipe being then pushed into the flue 60 opening until it reaches a point adjacent the bolt 19. The plate 15 at the curved end thereof is possessed of a great amount of 65 resiliency so that it will bear frictionally against the inner face of the stove pipe and hold the same tightly against the lower plate 13.

Thus to seat the pipe within the flue opening, it is only necessary to loosen the nut 22, rest the plate 13 on the lower wall of the flue opening and then draw the plates 13 and 14 so as to engage the ring 16 and the downturned portion 23 against the inner and 70 outer faces of the front wall of the flue. The nut is then screwed tight so as to prevent the plates slipping and also to hold down the inner end of the intermediate plate. The stove pipe is then inserted in the 75 flue opening so that the lower portion thereof passes between the plates 13 and 15 and is held frictionally therein. This device will effectively prevent the stove pipe from slipping out of the flue opening or sliding in 80 too far and interfering with the draft.

What is claimed is:

The combination with a chimney having a flue opening, with a stove pipe disposed therein, of a stove pipe holder comprising 90 an upper plate, a lower plate and an intermediate plate, the lowermost of the plates being provided on its outer end with a depending member for engagement with the wall of a room adjacent to the flue opening, 95 the intermediate plate being resilient and having its outer end curved upwardly and disposed over the depending end of the first-named plate, the uppermost of the plates being slidably adjustable with respect to 100 the other plates and provided with a depending portion for engagement with the inner

wall of the flue below the opening, said first-named plate and intermediate plate being arranged to receive and hold a portion of a stove pipe therebetween and within the flue opening, and a bolt disposed through all of said plates and acting as a stop for the inner end of the stove pipe.

Copies of this patent may be obtained for five cents each, by addressing the "Commissioner of Patents, Washington, D. C."

In testimony whereof, I affix my signature, in the presence of two witnesses.

STEPHEN M. SOULE.
